UNITED STATES PATENT OFFICE.

CHARLES L. NEWCOMB, OF HOLYOKE, MASSACHUSETTS, ASSIGNOR TO THE DEANE STEAM PUMP COMPANY, OF SAME PLACE.

VERTICAL AIR-PUMP FOR MOIST AIR OR GASES.

SPECIFICATION forming part of Letters Patent No. 613,466, dated November 1, 1898.

Application filed August 3, 1896. Serial No. 558,117. (No model.)

To all whom it may concern:

Be it known that I, CHARLES L. NEWCOMB, a citizen of the United States, residing at Holyoke, in the county of Hampden and State 5 of Massachusetts, have invented a new and useful Improvement in Vertical Air-Pumps for Moist Air or Gases, of which the following is a specification, accompanied by drawings, forming a part of the same, in which—
10 Figure 1 represents a perspective view of an air-pump embodying my invention. Fig. 2 is a front elevation of the supporting-framework of one of the pump-cylinders, with the pump-cylinder shown in central vertical section; and Fig. 3 is a top view of the cylinder.
15 Similar letters refer to similar parts in the different figures.

My invention relates to that class of air-pumps for pumping air or gases which are more or less charged with moisture; and it consists in certain features of construction and arrangements of parts, as hereinafter described, and set forth in the annexed claims.
20 Referring to the drawings, Fig. 1 represents an air-pump having two pumping-cylinders operated from a single driving-shaft, and as the two pumping-cylinders are duplicates I have confined my description to one 25 of the cylinders, which I have shown in sectional view in Fig. 2.
30 A denotes the base or bed plate, supporting a columnar framework B B, upon which are mounted the pumping-cylinders C C, inclosing pistons carried upon piston-rods connected with reciprocating cross-heads D D, driven in the usual manner from a shaft E, rotated through a belt-pulley E'.

Referring to Fig. 2, F denotes a reciprocating piston, and F' its piston-rod.

An air-chest G, Fig. 3, is formed upon the side of the cylinder, communicating, by means of a pipe G', with a tank or receptacle from which the air or gas is to be exhausted. The 35 air-chest G communicates with the interior of the pump-cylinder C by means of a passage G², Fig. 2, holes G³ G⁴, and air-passages G⁵ and G⁶, the hole G³ and air-passage G⁵ and the hole G⁴ and air-passage G⁶ being alternately brought into communication by 40 means of a reciprocating valve H, the sliding

movement of the valve H also alternately opening the passages G⁵ and G⁶ to an exhaust-chamber I, which is inclosed within the shell J. The shell J is open at the top, as at J', 55 allowing the contents of the cylinder to be exhausted at each reciprocating movement of the piston through the passages G⁵ and G⁶ and chamber I into the open air. The lower end J² is closed, and the shell is provided with a flange J³ at its sides and lower end, which 60 is attached by bolts J⁴ to the side of the cylinder. The valve H is carried upon a reciprocating stem H', which passes through a hole in the bottom of the shell J and is surrounded 65 upon the inner side of the shell by a cone-shaped boss J⁵, which carries the drip from the center into the annular trough J⁶.

The cylinder C has its lower head K integral with the sides of the cylinder and with 70 its central section raised or dome-shaped, as at K', and provided with a central opening concentric with the piston-rod F', forming an annular recess K², which communicates at the bottom with the cylinder-chamber by means 75 of a passage K³, having a slight inclination, sufficient to allow the products of condensation which may be caught in the chamber K² to flow into the cylinder-chamber. The chamber K² is closed at the bottom by the stuffing-box K⁵, attached by its flanges K⁴. The piston F is raised or dome-shaped in its central section, as at F², and the upper head K⁶ is correspondingly raised in its central section, as at K⁷, to permit the upward movement of 85 the piston to the end of the cylinder and is removably attached to the cylinder by bolts K⁸.

During the operation of the pump the condensed liquid, which collects upon the upper surface of the piston is held upon the lower 90 annular section K⁹, from which it flows at each upward stroke of the piston through a drip-pipe L and also through the passage G⁶ into the chamber I. The condensation collected upon the lower head K is gathered at the lower 95 annular trough-shaped section K¹⁰, from which it is conducted by a drip-pipe L², and the condensation collected in the trough J⁶ in the bottom of the shell J is removed through a drip-pipe L'.
100

What I claim as my invention, and desire to secure by Letters Patent, is—

1. In an air-pump comprising a vertical cylinder having a lower cylinder-head, a piston inclosed in said cylinder and a piston-rod passing through said lower head, said lower cylinder-head being provided with a raised central portion forming an annular trough-shaped section between said raised portion and the side of the cylinder and having a central recess concentric with the piston-rod and a passage between said central recess and said trough-shaped section, substantially as described.

2. In an air-pump, the combination with a vertical cylinder, of a reciprocating piston within said cylinder having its central section curved upwardly, whereby the condensation upon said piston is collected at the edges thereof, said cylinder having an exhaust-passage at its upper end, whereby the condensation is carried out of the cylinder at each upward movement of the piston, substantially as described.

3. In an air-pump the combination with a vertical cylinder having its sides and lower head integral, said lower head having its central section raised and extending into said cylinder, a removable upper head having its central section raised and extending without said cylinder, a reciprocating piston within said cylinder having its central section curved upwardly to correspond with the raised section of said lower cylinder-head, whereby the condensation above said piston is collected at the edges thereof, said cylinder having an exhaust-passage at its upper end, whereby the condensation is carried out of the cylinder at each upward movement of said piston, substantially as described.

Dated this 30th day of July, 1895.

CHARLES L. NEWCOMB.
